Primary Examiner — T Chase Nelson*Assistant Examiner* — Mary Claire Ramirez(74) *Attorney, Agent, or Firm* — Christopher Mayle; John Houvener; Bold IP, PLLC(57) **CLAIM**

The ornamental design for an animal collar, as shown and described.

DESCRIPTION

FIG. 1 is a front view of an animal collar showing the new design;

FIG. 2 is a back view thereof; and,

FIG. 3 is a bottom view thereof.

The broken lines shown in the drawings depict portions of the animal collar that form no part of the claimed design. The broken lines shown along the interior perimeter of the collar band depict stitching that forms no part of the claimed design.
